(57) **CLAIM**

The ornamental design for an electric shaver head, as shown and described.

DESCRIPTION

FIG. 1 is a perspective view of an electric shaver head; FIG. 2 is a front view of an electric shaver head of FIG. 1; FIG. 3 is a rear view of an electric shaver head of FIG. 1; FIG. 4 is a right side view of an electric shaver head of FIG. 1; FIG. 5 is a left side view of an electric shaver head of FIG. 1;

FIG. 6 is a top view of an electric shaver head of FIG. 1; and, FIG. 7 is a bottom view of an electric shaver head of FIG. 1.

The broken lines in the figures represent structure and boundaries that are not part of the claimed design of the electric shaver head, but rather show the environment in which the design is associated.

1 Claim, 7 Drawing Sheets
